UNITED STATES PATENT OFFICE.

JAMES PETTIBONE, OF AVONDALE, OHIO.

DESIGN FOR A BUTTON.

SPECIFICATION forming part of Design No. 19,924, dated June 24, 1890.

Application filed May 9, 1890. Serial No. 350,516. Term of patent 14 years.

To all whom it may concern:

Be it known that I, JAMES PETTIBONE, a citizen of the United States, and a resident of Avondale, in the county of Hamilton and State of Ohio, have invented and produced a certain new Design for the Face of a Button, of which the following is a specification, reference being had to the accompanying drawings, making a part thereof.

Figure 1 is a plan view of a button illustrating my design; and Fig. 2 is a sectional view on the line $\alpha\alpha$, Fig. 1.

The leading feature of the design resides in a convex button-face having thereupon a shield containing the emblems of a sheaf of wheat, a bundle of arrows, a mountain range in the background and above the sheaf of

wheat and arrows, and the rising sun over the mountain range. I have exhibited a plow opposite the sheaf of wheat and an expanse 20 of water for the background between the sheaf of wheat and the mountain range. I have also exhibited the circular boundaries of the shield as in relief, Fig. 2.

What I claim is—

The design for a convex button-face, substantially as shown and described.

In testimony whereof I have hereunto set my hand.

JAMES PETTIBONE.

Witnesses:

R. M. BICKERSTAFF,
C. W. MILES.
